DESIGN FOR A HANDBAG OR SIMILAR ARTICLE

Irving Pichel, New York, N. Y.

Application July 18, 1940, Serial No. 93,763

Term of patent 3½ years

To all whom it may concern:

Be it known that I, Irving Pichel, a citizen of the United States of America, residing in the city of New York, county of New York, and State of New York, have invented a new, original, and ornamental Design for a Handbag or Similar Article, of which the following is a specification, reference being had to the accompanying drawing, forming part thereof.

Fig. 1 is a front perspective view of a handbag or similar article showing my new design;

Fig. 2 is a rear perspective view thereof;

Fig. 3 is a fragmentary front perspective view thereof in open position, with the handle member turned downward and a portion of the bag shown broken away for convenience of illustration.

I claim:

The ornamental design for a handbag or similar article, as shown and described.

IRVING PICHEL.
